US00D978080S

(12) **United States Design Patent** (10) **Patent No.:** **US D978,080 S**
(45) **Date of Patent:** **** Feb. 14, 2023**

(54) **GENERATOR**

(71) Applicant: **EcoFlow Inc.**, Shenzhen (CN)

(72) Inventors: **Lei Wang**, Shenzhen (CN); **Haibin Zheng**, Shenzhen (CN); **Weibin Gao**, Shenzhen (CN)

(73) Assignee: **ECOFLW INC.**, Shenzhen (CN)

(**) Term: **15 Years**

(21) Appl. No.: **35/512,163**

(22) Filed: **Jun. 22, 2021**

(80) **Hague Agreement Data**

Int. Filing Date: **Jun. 22, 2021**

Int. Reg. No.: **DM/215096**

Int. Reg. Date: **Jun. 22, 2021**

Int. Reg. Pub. Date: **Jul. 16, 2021**

(51) **LOC (14) Cl.** **13-01**

(52) **U.S. Cl.**

USPC **D13/112**

(58) **Field of Classification Search**

USPC D13/112, 110, 107, 108, 103, 116, 106;
D21/333; D14/433

See application file for complete search history.

PLLC

(57) **CLAIM**

The ornamental design for a generator, as shown and described.

DESCRIPTION

1. Generator

2. Generator

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

1.11 alternate perspective view; and

1.12 another alternate perspective view.

Reproduction 1.1: front view of design 1; Reproduction 1.2: back view of design 1; Reproduction 1.3: left view of design 1; Reproduction 1.4: right view of design 1; Reproduction 1.5: top view of design 1; Reproduction 1.6: bottom view of design 1; Reproduction 1.7: perspective view (front, top, right side) of design 1; Reproduction 1.8: perspective view (back, bottom, left side) of design 1; Reproduction 1.9: perspective view (front, top, left side) of design 1; Reproduction 1.10: perspective view (back, bottom, right side) of design 1; Reproduction 1.11: usage state reference view of design 1; Reproduction 1.12: usage state reference view of design 1.

1 Claim, 12 Drawing Sheets
